UNITED STATES PATENT OFFICE.

ELEAZER KEMPSHALL, OF BOSTON, MASSACHUSETTS.

PLAYING-BALL.

SPECIFICATION forming part of Letters Patent No. 715,206, dated December 2, 1902.

Application filed August 19, 1902. Serial No. 120,193. (No model.)

To all whom it may concern:

Be it known that I, ELEAZER KEMPSHALL, manufacturer, a citizen of the United States, residing at 41 High street, in the city of Boston, county of Suffolk, and State of Massachusetts, have invented certain new and useful Improvements in Playing-Balls, of which the following is a specification.

My invention relates to improvements in playing-balls, and has for one of its objects to provide a ball which shall have its weight accurately centered, thereby rendering it truer in its flight than playing-balls as heretofore constructed.

15 A further object of my invention is to dispense with the use of a center piece, as already described in the specifications filed with my previous applications.

According to my present invention I dispense with the hard core and provide in place thereof a core or filling composed of a highly-elastic substance, preferably in the form of rubber tape, ribbon, strips, or threads, which is coiled or wound under severe tension and 25 inclosed in cups or hemispheres of plastic material, the whole being then subjected to high pressure. In same cases I may form the aforesaid coil or winding in two or more concentric portions, between which I may interpose a bulb or shell of celluloid, gutta-percha, or similar hard but resilient substance.

In order that my invention may be clearly understood and readily carried into effect, I 35 will now describe the same more fully with reference to the accompanying drawings, in which—

Figure 1 is a view, partly in section, of one form of playing-ball constructed in accordance with my invention. Fig. 2 shows a piece of the elastic material before being wound into a core. Fig. 3 shows the inner part or core of the ball with the cover or shell removed. Figs. 4 and 5 illustrate the preferred form of my invention.

45 Referring to the drawings, *a a* are strips, ribbons, or tapes of a highly-elastic substance, preferably rubber, wound or coiled under extreme tension to the required shape and 50 size to form the inner part or core of my improved ball, as shown in Fig. 3.

The material for forming the inner part or core may be in the form of a strip consisting of a thread fabric, such as elastic webbing; but I find tapes or ribbons of thin flat rubber give very satisfactory results, where it is desired to wind the material under a very high tension and to produce a hard but comparatively resilient inner part or core.

55 A represent the outer shell or cover formed of cups or hemispheres of a plastic substance, such as gutta-percha, in which the inner part or core of the ball is inclosed.

In the preferred form of construction shown in Figs. 4 and 5, *a' a'* represent the internal 60 hollow bulb or shell interposed between the windings *a a*. In this case the winding of the inner portion of the core proceeds until it has reached any desired diameter, preferably about one inch, and is then placed between 65 the halves or hemispheres *a' a'* of said bulb or shell. The winding of the elastic material *a* over or outside of these hemispheres is then resumed, and owing to the high tension at which it is wound the edges of the said cups 70 or hemispheres are brought closely together, so as to firmly grip the inner portion of the core. The winding of the rubber strips upon the outside of the hemispheres *a' a'* continues 75 until the core reaches approximately the diameter shown in Fig. 3, when it is inclosed in the cups or hemispheres *A A* and subjected to pressure.

What I claim, and desire to secure by Letters Patent of the United States, is—

85 1. A playing-ball comprising a plurality of hard shells and having its central portion composed of highly-elastic material wound under tension and also having soft elastic material between said shells.

90 2. In a playing-ball the combination of an external shell, an inner shell, a layer of soft springy material between said shells, and a filling for said inner shell comprising multitudinous windings of highly-tensioned elastic material, substantially as described.

95 3. In a playing-ball, the combination of an external shell, a plurality of spheres therein each consisting of concentric windings of elastic material under tension, and means for 100 keeping said spheres separate from each other, substantially as described.

4. In a playing-ball, the combination of an external shell, a plurality of concentric spherical windings composed of highly-tensioned elastic material, and a shell of hard resilient material between said windings, substantially as described.

5. In a playing-ball, the combination of a winding of highly-tensioned elastic material forming the core of the ball, a shell of hard resilient material inclosing said winding, a winding of highly-tensioned elastic material exterior said shell, and another shell inclosing said second winding, substantially as described.

15 6. In a playing-ball the combination of a plurality of windings of highly-tensioned elastic material, hemispheres of hard resilient material interposed between said windings and adapted to firmly grip the inner winding, and 20 hemispheres of plastic material exterior to said windings and welded together at their edges by pressure, substantially as described.

7. A playing-ball comprising a core of tense windings of rubber, a thin hard shell thereon, 25 a softer layer of resilient material upon said shell, and a hard cover.

8. A playing-ball comprising a core of tense windings of rubber, a thin hard shell thereon, a softer layer of resilient material upon said 30 shell, and a hard cover holding said resilient material under compression.

9. A playing-ball comprising a core consisting of tense windings of rubber, a thin hard springy shell thereon, tense windings of rubber 35 upon said shell and a cover of hard plastic material.

10. A playing-ball comprising a core consisting of tense windings of rubber, a hard flexible shell thereon, tense windings of rubber 40 upon said shell, and a cover of hard plastic material holding the same under compression.

11. A playing-ball comprising a core of soft resilient material, a thin hard shell thereon,

tense windings of rubber upon said shell, and a cover of gutta-percha.

12. A playing-ball comprising a core of soft resilient material, a hard springy shell thereon, tense windings of rubber upon said shell, and a cover of gutta-percha holding the same under compression.

13. A playing-ball comprising a core of soft rubber, a shell thereon of harder plastic material, a softer layer of resilient material upon said shell, and a hard cover.

14. A playing-ball comprising a core of tense windings of rubber, a flexible celluloid shell thereon, a softer layer of resilient material upon said shell, and a hard cover holding said resilient material under compression.

15. A playing-ball comprising a core consisting of tense windings of rubber, a flexible celluloid shell thereon, tense windings of rubber upon said shell, and a cover of hard plastic material.

16. A playing-ball comprising a core consisting of tense windings of rubber, a flexible celluloid shell thereon, tense windings of rubber upon said shell, and a cover of hard plastic material holding the same under compression.

17. A playing-ball comprising a core of soft resilient material, a celluloid shell thereon, tense windings of rubber upon said shell, and a cover of gutta-percha.

18. A playing-ball comprising a core of soft resilient material, a celluloid shell thereon, 75 tense windings of rubber upon said shell, and a cover of gutta-percha holding the same under compression.

In testimony whereof I have hereunto set my hand, in presence of two subscribing witnesses, this 8th day of August, 1902.

ELEAZER KEMPSHALL.
